His Attorney.

UNITED STATES PATENT OFFICE.

HARTT H. EASON, OF CHICAGO, ILLINOIS, ASSIGNOR TO ACORN BRASS MANUFACTURING COMPANY, A CORPORATION OF ILLINOIS.

LAMP AND FEEDING-TUBE CONNECTION AND SUPPORT.

No. 909,069.

Specification of Letters Patent.

Patented Jan. 5, 1909.

Application filed April 25, 1908. Serial No. 429,277.

To all whom it may concern:

Be it known that I, HARTT H. EASON, a citizen of the United States, residing in Chicago, in the county of Cook and State of Illinois, have invented certain new and useful Improvements in Lamp and Feeding-Tube Connections and Supports, of which the following is a specification.

This invention relates to that class of gas lamps or fixtures having a supporting bracket which is provided with an upper ring portion adapted to support the hollow wires or feeding tubes forming part of a gas or gasoline lighting system, and having depending clamping arms adapted to support and permit the adjustment of the lamp fixture proper after the hollow wires or tubes of the lighting system are first mounted in position and supported by one or a series of such clamping and tube-supporting bracket members.

The principal object of the invention is to provide a simple, economical and efficient combined hollow wire and gas lamp or fixture supporting bracket.

A further object of the invention is to provide a combined hollow wire and gas lamp or fixture supporting bracket, having a grooved upper ring portion and depending clamping arms, so constructed that a series of such brackets may be employed to support the horizontal or main wires or tubes of a gas or gasoline lighting system, and enable the lamps or fixtures to be mounted and adjusted in said brackets, and the tubes leading to the lamps or fixtures to be connected with the tubes of the main wiring or feeding tube system after the laying of the feeding tubes of the main system and the mounting of the clamping and tube supporting brackets is completed.

Other and further objects of the invention will appear from an examination of the drawings and the following description and claims.

The invention consists in the features, combinations, and details of construction hereinafter described and claimed.

In the accompanying drawings Figure 1 is a view in side elevation of a plurality of my improved upper bracket members in position; Fig. 2, a central sectional view in elevation of my improved tube supporting and fixture clamping bracket member connected with

a gasoline lamp and showing the manner of connecting and supporting the tubes and fixture; Fig. 3, a plan view of the bracket shown in Figs. 1 and 2, and Fig. 4, a bottom view of the same.

In constructing a combined lamp and feeding tube supporting and connecting bracket in accordance with my improvements, I provide a bracket or bracket member *a* formed preferably of cast metal and consisting of an upper ring portion *b* having radial grooves *c* preferably in its upper side, in position to hold hollow wires or feeding tubes *d* in position between the upper ring or grooved wire-supporting portion of the bracket and ceiling or support to which the bracket is to be attached. Depending arms *e* preferably integral with the upper feeding-tube supporting or ring portion of the bracket, extend downward and toward the center on opposite sides of the vertical or axial center of the ring portion of the bracket and are each provided with substantially semi-circular grooves *f* at their lower ends respectively. These grooves form a substantially cylindrical opening between the lower ends of the said arms, which is adapted to receive the upper portion of a fixture, *g* which may be in the form of a chandelier, depending tubular arm or any other desired type of lamp bracket proper or supporting device connected directly with or forming a direct support for a lamp or burner, and having a smooth or non-threaded upper portion adapted to be clamped between and adjusted to the desired position with relation to the bracket member or bracket *a*, and the feeding tubes supported thereby.

The depending arms *e* are sufficiently flexible to permit them to be spread apart very slightly but to a sufficient extent to admit the upper end of the fixture or lamp engaging and supporting member *g* when such spreading is necessary by reason of the size of the member *g*. Ordinarily, however, the spreading of the arms is not necessary or desirable, and their flexibility is desirable principally for the purpose of enabling them to be clamped to the member or lamp supporting tube *g* in an efficient manner, so as to enable the latter and the feeding tube or hollow wire *h* contained therein to be adjusted with the necessary degree of accuracy to be prop-

erly connected with the T-joint *i* and thereby with the feeding tubes *d* by means of flanged nuts *s* and *o'* and nipples *t*. The lower end of each depending arm *e* is provided with a laterally projecting portion *j* on each side thereof suitably perforated, and in one or both sides suitably threaded, to admit a clamping screw *k*. These screws may each be provided with a nut if desired, and are adapted to clamp the spring arms *e* firmly into supporting engagement with the upper cylindrical portion of the depending member *g*.

The upper ring portion of the bracket *a* is provided with a plurality of perforations *l* for receiving screws, not shown, by means of which the bracket is secured to the ceiling of a room or to a desirable support, and the upper radial portions *n* between the radial grooves *c* have their upper surfaces all on the same plane and are arranged at such close intervals that the bracket may be turned to any desired position to enable the screws to enter a rafter or any desired portion of a rafter or other support without seriously affecting or making it necessary to change the position of the feeding tubes or hollow wires by reason of the positions of the grooves or upper radial portions of the ring which are between the grooves.

30 By the above arrangement it will be seen that an entire system of hollow wiring may be completed, all of the feeding tubes which compose the system being supported by the above described combined hollow wire and fixture or lamp supporting bracket members.

Any desired number of said bracket members may be thus mounted in positions corresponding with desired positions in which the fixtures or lamps are to be mounted.

40 The brackets support the feeding tubes in the grooved portion of the upper rings so as to hold them in just the position in which they are to be used. The depending arms of each of these bracket members being smooth, or 45 without threads, and the upper end of the fixture or lamp which is to be clamped between said arms, being likewise smooth and free from threads, it will be readily seen that the tubes which extend vertically inside of

50 the fixture may be fixed to the fixture or lamp in the factory, and the connection with the hollow wires of the feeding tube system may be made after the construction of the system is complete and after the improved upper bracket members are mounted in place. The facility with which the fixtures may be mounted and connected with the hollow wires or feeding tubes of a lighting system is thus greatly increased. The facility

60 with which the parts of the fixture including the vertical tube *h* the outer tube or fixture member *g*, the nut *o*, the nipple *p*, the nut *q* and the lamp *r*, can be assembled is also greatly increased, and the fit between the

vertical tube *h* and the horizontal or main 65 gas or oil supply tubes may thus be made practically perfect after the entire system of main feeding tubes is laid, and notwithstanding the differences which occur in practice in the lengths of the tubes *h* with relation to the 70 fixture members *g*.

I claim:

1. A bracket of the class described having an upper ring portion provided with radial openings for receiving feeding tubes, and 75 having flexible depending arms on the under side of said ring portion extending downward and inward and provided with a space between the ends of said arms and means for clamping said depending arms together. 80

2. In a bracket of the class described, the combination of a ring portion provided with radial grooves in its upper side for receiving feeding tubes to be supported by the bracket, and having flexible depending arms on the 85 under side of said ring portion extending downward and inward and provided with a space between the lower ends of said arms, and means for clamping said arms in engagement with a device to be supported thereby. 90

3. In a bracket of the class described, the combination of an annular upper portion provided with radial openings for receiving feeding tubes and having flexible depending arm portions on its under side extending downward and inward and normally out of contact with each other, and screw mechanism mounted in and connecting the lower ends of said arm portions. 95

4. In a bracket of the class described, the 100 combination of an upper ring portion provided with radial grooves in its upper side and having perforations therethrough for receiving bracket supporting screws, said ring portion having radial body portions between 105 the grooves for engaging the sides of feeding tubes to be mounted in the grooves, flexible depending arms integral with said ring portion extending downward and inward therefrom and having a space between their adjacent lower ends for receiving a portion of a gas lamp supporting arm therebetween, and means for clamping the flexible arms in engagement with the gas lamp supporting arm. 110

5. In a bracket of the class described, the 115 combination of an upper ring portion provided with radial grooves in its upper side, and having flexible arms extending downward and inward on the under side of said ring portion and each having a substantially semicircular vertical groove in its lower end forming a substantially circular opening between the ends of said arms, feeding tubes mounted in the upper grooved portion of the bracket and adapted to be connected with a 120 source of combustible fluid supply, a feeding tube extending downward between the depending arms and connected at its upper end

with the feeding tubes supported by the ring portion of the bracket and adapted to communicate with a gas burner, a gas burner or lamp supporting member having a tubular portion in engagement with the flexible arms of the bracket and encircling the downwardly extending feeding tube, and means for clamp-

ing the flexible arms in engagement with the tubular portion of said lamp supporting member.
